CARD FILE

Filed June 22, 1927

INVENTOR
Wentworth H. Shortridge
by Edward A. Lawrence,
his attorney.

UNITED STATES PATENT OFFICE.

WENTWORTH H. SHORTLIDGE, OF AVALON BOROUGH, PENNSYLVANIA.

CARD FILE.

Application filed June 22, 1927. Serial No. 200,649.

More particularly my invention relates to that character of card files wherein the cards are arranged in overlapping relation in a tray which is frequently arranged to be employed as a drawer.

Among the novel features characteristic of my invention are the following.

The provision of improved means whereby the cards may be inserted into and removed from the tray.

The provision of improved means whereby individual cards may be inserted into their proper places in a series of cards already mounted on the tray without dislodging the other cards of the series, and likewise whereby individual cards may be conveniently removed from the tray.

The provision of new and improved means for laterally offsetting individual cards relative to the main body of cards in the series without moving them relative to their carriers.

The provision of means whereby individual cards may be disposed vertically to the main body of the cards.

The provision of improved means for mounting the cards on their carrier bars so that they can be readily attached thereto or removed therefrom.

Other novel features of construction, and also of arrangement of parts will appear from the following description.

In the accompanying drawings, wherein I have illustrated the best embodiment of the principles of my invention, Fig. 1 is a plan view showing a series of index cards mounted in a tray; Fig. 2 is a front end view of the same; Fig. 3 is a longitudinal section of the same but also showing one of the cards disposed in a substantially vertical position; Fig. 4 is an enlarged detail in section taken along the line IV—IV in Fig. 1 and showing one of the journal clips mounted in the tray; Fig. 5 is a perspective of one of the journal clips employed at one side of the tray, the left side in Fig. 1; Fig. 6 is a similar view of one of the clips employed at the other side of the tray; Fig. 7 is a detail showing a pair of opposed journal clips, illustrated in section, with a carrier bar mounted thereon and arranged for the vertical disposal of its card; Fig. 8 is a fragmentary detail showing the bar arranged for disposing the card in its

offset position; Fig. 9 is a similar view showing the carrier bar arranged for disposing the card in its normal position wherein it is aligned with the remaining cards of the series; Fig. 10 is a plan view showing a modified form of carrier bar; Fig. 11 is an elevation or edge view of the same; Fig. 12 is a view in cross-section of the carrier bar illustrated in Fig. 7, and Fig. 13 is a broken elevation of one of the index cards showing its lower portion perforated for mounting on the carrier bar illustrated in Figs. 10 and 11.

Referring first to Figs. 1 to 9, inclusive, 1 is the tray, which, as has already been stated, is usually employed as a drawer, and which preferably has a continuous bottom. The lateral edges of the tray 1 are provided with the vertical flanges 2 whose upper edges are turned inwardly and downwardly to form a downwardly opening groove 3.

Along the bottom of the tray 1 adjacent to each of its side flanges 2 is fixed, as by riveting or soldering, a metal strip 4 whose outer edge is spaced slightly from the flange of the tray and bent upwardly to form with the flange an upwardly opening groove 5.

6 and 6^a represent the two types of journal 80 clips in use, the clips 6 being employed at the left side of the tray as shown in Fig. 1 and the clips 6^a at the right side of the tray. These clips are made by cutting and bending up a strip of somewhat resilient metal to form 85 a box body open at the rear side and having upwardly and downwardly disposed tongues 7 and 8, respectively. The clips are put in position by compressing them so that the tongues 7 and 8 may be slipped into the 90 grooves 3 and 5 and then the clips are allowed to expand, thus holding the clips in position at the sides of the trays. The top walls of the clips may be provided with holes 9 so that a pencil point or other tool may be used 95 to compress the clips and thus disengage them from their seats in the grooves 3 and 5.

The clips 6 are provided in the front faces with holes 10 of substantially the inverted key-hole shape shown in Fig. 5, the slotted 100 or narrow portion being above. The clips 6^a are provided with the oval holes 11 with their longer axes vertical.

The preferred form of carrier bars is shown at 12, being a relatively narrow, flat strip of 105 metal which is preferably non-flexible. At

one end said bar is provided with a reduced portion 13 of sufficient width to be both slidably and rotatably held in the hole 11 of the clip 6^a. The other end has a head 14 of the full width of the body of the bar, and between the head and the body of the bar a reduced portion or neck 15 which when vertically disposed will slide longitudinally in the hole 10 of the clip 6 but will not turn therein. At each end of the portion 15 are provided a pair of opposed notches 16 and 16^a respectively, the neck of metal between the members of each pair being sufficiently narrow to permit the bar 12 to rotate when the notches are engaged with the walls of the lower or circular portion of the hole 10 in the clip 6. The portion 13 of the bar 12 is also provided with a notch 17 which is positioned to engage the wall of the hole 11 when the portion 15 of the other end of the bar is engaged in the hole 10 and the bar is on edge.

An outer corner of the head 14 is beveled as at 14^a to facilitate mounting of the clips 6 thereon.

Secured to the bar 12 are the card clips 18 which may be formed by a piece of doubled-over spring metal soldered or otherwise secured to one of the flat faces of the bar 12. The clips 18 extend in the opposite direction, relative to the bar 12, from the notch 17, and the cards 19 are mounted on their carrier bars by having their top edges slipped down into the clips 18.

In Figs. 10 and 11 I show a modified means of attachment of the card to its carrier bar. Thus the bar 12^a is provided with a plurality of cut-out and bent out tongues, such as three, 20, 20^a and 20^b, the first two facing in the same direction while the remaining one, one of the end tongues, faces in the opposite direction. The card 19, indicated in dotted lines in Fig. 10, is provided with vertical cuts 21 and 21^a near its upper edge, and the card is first slid from right to left in Fig. 10 to engage the cuts 21 and 21^a with the tongues 20 and 20^a and the left end of the card is then bent in to engage the end of the card under the tongue 20^b, and the card then released. To remove the card, it is bent to first disengage the end of the card from the tongue 20^b and then slid from left to right to disengage the cuts from the other tongues.

In Fig. 7 I show two spring clips 22, shorter than the clips 18 and preferably mounted on the opposite side of the carrier bar. These clips 22 are intended for such purposes as to hold a narrow label card on the bar so that when the card 19 is removed, its proper carrier bar will be designated to indicate that the corresponding card has been removed.

If desired cut-out tongues like 20, 20^a and 20^b may be formed in the carrier bar for the same purposes.

In Fig. 9 the relation between the end of the carrier bar 12 and the left-hand clip 6, when the cards are in their normal and alined position, is illustrated, the inner pair of notches 16 registering with the hole 10 in the clip 6, and the bar being free to rotate relative to the clips 6 and 6^a so that the card may be turned down into its normal overlapped relation to the other cards or it may be turned up and back to expose the card or cards below.

The vertically elongated shape of the hole 11 enables the bars to rise sufficiently to cause the cards to lie flat on each other.

In Fig. 8 the carrier bar is shown shifted so to bring the notches 16^a into registration with the hole 10, thus laterally offsetting the card mounted on the bar relative to the other cards, as illustrated at 19^a in Fig. 1.

In Fig. 7 the carrier bar is shown shifted into a position wherein the portion 15 of the bar engages the hole 10. As this portion of the bar is of such width as to extend up into the slotted upper portion of the hole 10, thus holding the bar on edge, the corresponding card is thus held vertical, as illustrated at 19^b in Fig. 3. The notch 17 in the other end of the bar is so located that it may be engaged with the hole 11 in the clip 6^a to hold the bar against accidental longitudinal movement while the card is elevated at 19^b.

The bar may readily be shifted longitudinally by first turning the bar and card up vertically and raising the bar so that the notches therein are disengaged from the clips.

The advantages of being able to offset one or more of the cards relative to the remainder is recognized in posting or other work. The advantage of elevating one or more of the cards is also apparent in that it enables a card which may be required for reference to be placed in a conspicuous and convenient position relative to the other cards.

When a card is to be inserted on the tray, the clips are first placed on its ends and they are then compressed and moved outwardly on the bar and sprung into position as illustrated. When a card is to be removed with its carrier bar, the point of a pencil or a suitable tool is inserted in the holes 9 of the clips to compress them so that they are readily released from the tray and slid inwardly on the bars to clear the flanges of the tray.

If desired the cards may be placed on or taken off the bars while the latter are mounted in the tray.

The use of the clips in which the ends of the bars are engaged, greatly facilitates the insertion of the bars into the tray and their removal therefrom. It also enables a card to be conveniently inserted in place or removed therefrom between cards already mounted on the tray.

The insertion and removal of the cards does not involve the bending of the carrier

bars and the same may be of stiff material, and thus do not become crooked or distorted thereby preventing the cards from lying flat and interfering with their being swung up and down.

The cards may be individually offset without moving them relative to their carrier bars, thus preventing wear on the cards or the impairment of their attachment to their carrier bars.

What I desire to claim is:—

1. In a card file of the character described, the combination of a support, journal members detachably mounted in opposed pairs on said support, card-carrier bars having their ends slidable in said members, and means whereby when said bars are slid into one position relative to said journal members said bars are held against rotation and when 20 said bars are slid into another position relative to said journal members said bars are rotatable relative to said journal members.
2. In a card file of the character described, the combination of a support having journals arranged in opposed pairs, card-carrier bars having their ends inserted in said journals and arranged for both rotary and longitudinal sliding movement relative to said journals whereby individual cards may be 25 offset from the remainder of the cards, and means for preventing accidental displacement of the cards from their normal and offset positions.
3. In a card file of the character described, the combination of a support, a plurality of pairs of opposed journals on said support, and card-carrier bars having their ends inserted in said journals and longitudinally slidable therein, the ends of said bars and the 30 journals being shaped so that when in one position relative to said journals a bar is rotatable in the corresponding journals but when in another position said bar is held against rotation.
4. In a card file of the character described, the combination of a support, a plurality of pairs of opposed journals on said support, and card-carrier bars having their ends inserted in said journals and longitudinally 35 slidable therein, the ends of said bars and the journals being shaped so that when in either of two positions relative to the corresponding journals a bar is rotatable therein but when in an intermediate position said bar is held against rotation.

5. In a card file of the character described having the combination of a support, a plurality of pairs of opposed journal-openings, one journal-opening of a pair being non-round, and card-carrier bars having their ends inserted in and slidable in said journal openings, said bars having reduced portions which when engaging the non-round journal openings permit the rotation of the bars and other portions which when engaging said

non-round journal openings prevent the rotation of said bars.

6. In a card file of the character described having the combination of a support, a plurality of pairs of opposed journal-openings, one journal-opening of a pair being non-round, and card-carrier bars having their ends inserted in and slidable in said journal-openings, said bars being provided with spaced-apart reduced portions which when engaged in said non-round journal-openings permit the bars to rotate and intermediate portions which when engaged in said journal-openings prevent the rotation of said bars.

7. In a card file of the character described having the combination of a support, a plurality of pairs of opposed journal-openings, one journal-opening of a pair being non-round, and card-carrier bars having their ends inserted in and slidable in said journal-openings, said bars being provided with spaced-apart reduced portions which when engaged in said non-round journal-openings permit the bars to rotate and intermediate portions which when engaged in said journal-openings prevent the rotation of said bars, and means for preventing longitudinal movement of a bar when its said intermediate portion engages the journal-opening.

8. In a card file of the character described having the combination of a support, a plurality of pairs of opposed journal-openings one journal-opening of a pair being non-round, and flat metal card-carrier bars having their ends inserted in and slidable in said journal-openings, one extremity of each of said bars being provided with two portions of reduced width which when engaged with the non-round journal-opening permits the bars to rotate and with an intermediate portion of greater width which when engaged with the non-round journal-opening holds the bar against rotation.

9. In a card file of the character described having the combination of a support, a plurality of pairs of opposed journal-openings, one journal-opening of a pair being non-round, and flat metal card-carrier bars having their ends inserted in and slidable in said journal-openings, one extremity of each of said bars being provided with two portions of reduced width which when engaged with the non-round journal-opening permits the bar to rotate and with an intermediate portion of greater width which when engaged with the non-round journal-opening holds the bar against rotation, and means for preventing accidental longitudinal movement of a bar when said intermediate portion is engaged with said non-round journal-opening.

10. In a card file of the character described, the combination of a support, journals arranged in opposed pairs on said support, and card-carrier bars having their ends inserted in said journals and arranged for both rotary

and longitudinal movement relative to said journals whereby individual cards may be offset from the remainder of the cards.

11. In a card file of the character described, the combination of a support having journals arranged in opposed pairs, card-carrier bars having their ends inserted in said journals, means for attaching cards to one side of the bars and for attaching labels to the other side of the bars.

12. In a card file of the character described, the combination of a support, a card-carrier

bar arranged to be mounted on the support, a pair of tongues on said bar extending in the same direction and a third tongue adjacent to the end of the bar facing in the opposite direction, and a card having openings through which said first-named tongues extend and having its edge inserted beneath the third tongue.

Signed at Pittsburgh, Pa., this 20th day of June, 1927.

WENTWORTH H. SHORTLIDGE.
